UNITED STATES PATENT OFFICE.

ALBERT V. LOCKE, OF BELMONT, MASSACHUSETTS.

VEHICLE ALARM.

Application filed February 2, 1926. Serial No. 85,593.

This invention relates to an alarm, and more particularly to an audible alarm for use in connection with motor driven vehicles.

5 The primary object of the invention is to provide means to cause an audible alarm to sound when an unauthorized person attempts to move a vehicle from the position or location in which it was left by the

10 owner or authorized operator.

It is also an object of the invention to produce an inexpensive alarm of simple structure which may be applied to existing as well as new vehicles at but slight 15 cost and expenditure of time, and without the services of a skilled mechanic.

20 It is a further object of the invention to produce an alarm which will be released for operation by mechanism which must be operated before the vehicle can be moved either by its own power or by towing.

Another object of the invention is to produce an alarm of the above class which is arranged to be normally inoperative but 25 which may be instantly, and without particular care or attention set to operate, and when once so set may not be returned to its inoperative position, except by those acquainted with the particular alarm, without 30 causing it to sound its warning.

A still further object of the invention is to so arrange the alarm setting mechanism that the control for setting it for its 35 inoperative position may be shifted or changed at will so that the numeral or character which aids in indicating that the alarm is in that position may be changed as often as desired, and to differ from other vehicles likewise equipped with the alarm.

40 Other objects of the invention will be fully understood from a description of the drawings and the claims hereinafter given.

Of the drawings.

45 Figure 1 represents a vertical longitudinal section through a sufficient portion of a vehicle to enable the invention to be understood.

Figure 2 is a view of a portion of Figure 1 looking in the direction of the arrow A.

50 Figure 3 is an enlarged detail to be referred to.

Figure 4 is a view partly in elevation and partly in section taken on approximately the line 4—4 Figure 2.

Figure 5 is a section on the line 5—5 55 Figure 4.

Figure 6 is an underside view of a portion of the alarm mechanism shown in Figure 4, the gong or bell portion being removed. 60

Figure 7 is a detail of a portion of the alarm setting mechanism.

Figure 8 is a detail of the gong hammer locking device.

Like characters represent like parts 65 throughout the several figures of the drawings.

The drawings herewith illustrate one of the various ways in which the invention might be applied to a vehicle, but it will be 70 understood that it is not the intention to limit it to the precise construction and arrangement shown as changes might be made therein without departing from its spirit and scope. 75

In the present instance the alarm 10 is preferably secured to the underside of the foot board 11 and comprises a base plate 12 having the ribs 13 and 14 extending therefrom to which a plate 15 is suitably 80 secured.

The said plate 15 serves to carry the gong or bell 16 and the actuating mechanism therefor, the said gong being of the well known mechanical push type, and comprising 85 a bottom cover portion 17, and a gong or bell portion 16 which serves as a cover for the usual spring 19, gears 20 and 21, escapement 22 and hammer 23, and which also serves as a means to wind the said 90 spring 19 as is usual and well known in bells of this type.

The escapement 22, which is at times actuated by the ratchet wheel 24, has an arm 25 secured thereto at the end of which 95 is the hammer 23.

A flat spring member 26 having one end 27 fast to the bottom cover 17 has at its free end an extension 28 which is provided with a rounded or cam shape portion 29 arranged to engage the arm 25 of the hammer 23 and through it, normally hold the said es- 100

capement in such close engagement with the ratchet 24 that actuation of the hammer is restrained.

Fast to the plate 15 is a bracket 30 to which is pivoted at 31 a lever 32, the said lever having a hook 33 at one end thereof, and a pin 34 pivoted at the other end, and being normally under the control of a strong spring 35 which tends to rock said lever in the direction of the arrow B, see Figures 3 and 4 of the drawings.

The plates 12 and 15 are provided with suitable bearings 36 and 37 respectively for the shaft 38 of a disk or abutment member 39, the said shaft protruding through the foot board 11, and having a dial 40 secured thereto in such manner as to be shifted about the shaft so that the numeral or character thereon which registers with the stationary indicator 41 on the foot board 11 when the alarm is set in inoperative position may be changed at will.

The base of the bracket 30 extends toward the right, and is somewhat thinner to receive the disk or portion thereof, between it and a guide plate 42 fast with the bracket 30 said guide plate having a hole for the guidance of the pin 34 which is normally forced against a blank spot on said disk when the alarm is set in inoperative position.

The disk 39 is preferably provided with a plurality of holes 43 located adjacent its perimeter, the said holes being closely arranged and preferably counter sunk so that the pin 34 under the action of the spring 35 will enter one or another of them even though the pin and a hole do not exactly register.

The series of holes 43 around the edge of the disk 39 is interrupted by a blank spot 44 against which the pin 34 is forced when the alarm is set for inoperative position, holding the said disk from movement by the combined action of the strong spring 35 and the frictional contact afforded between the disk 39 and the extension of the base of the bracket 30.

When the disk is set as just described the dial 40 may be released from its secured position on the shaft 38, and returned thereon until the desired numeral or character chosen to register with the indicator 41 when the blank 44 is under the pin 34, registers therewith, whereupon the said dial will be firmly secured to the shaft 38 by a set screw 45 or in any suitable manner.

In order to turn the disk 39 so that the blank 44 will be removed from the path of the pin 34, and a hole 43 substituted therefor to set the device for operation, it is necessary to relieve the pressure of the pin 34 from the said disk.

The alarm is not intended to be set for operation excepting when the vehicle has

been brought to a stop at which time it is usual and often times compulsory to apply the emergency brake to retain the vehicle in stopped position.

In view of this fact the emergency brake lever conveniently lends itself to a successful application of the invention in a simple manner; but it will be understood that other vehicle control devices might be employed with good results so long as those devices are such that they must be operated prior to moving the vehicle.

For the purpose of illustration I have shown one form of emergency brake lever 50 pivoted at 51 to a housing not shown, and having a link 52 preferably pivotally riveted to one end of a bell crank 53 which has likewise secured at its other end a link 54 the free end of which has an elongated slot 55 therein to receive the hook 33 of the lever 32.

During the ordinary running of the vehicle or at such times as the emergency brake is not put to use, the lever 50 and connections therefrom to the lever 32 will occupy approximately the positions shown in Figures 1, 4 and 5 of the drawings.

When the vehicle has come to a stop and the emergency brake is applied the lever 50 will be pulled in the direction of the arrow C, Figure 1 of the drawings, causing the bell crank 53, through the link 52, to be rocked and pull the link 54 to the left, see Figures 1, and 3 to 5 inclusive, so that at the last portion of the movement of the lever 50 the end of the elongated slot 55 will be brought into contact with the hook 33, and but slight further movement of the said lever 50 will cause the lever 32 to be rocked against the action of the spring 35 sufficiently to relieve the pressure of the pin 34 against the blank 44 of the disk 39.

With the emergency brake thus applied, and the restraining pressure released from the disk 39, the dial 40 may now be turned in one direction or the other any number of degrees less than 360, or a sufficient distance to remove the blank 44 from beneath the pin 34, and the device will be set for operation providing of course that the emergency lever has been locked in its applied position by the usual locking means, a portion of which is indicated at 56 in Figure 1 of the drawings.

At this time one of the holes 43 will be in register with the pin 34, and in the event that an unauthorized person should attempt to move the vehicle, an attempt to release the emergency lever 50 will cause the pin 34 to enter and pass through a hole 43 and contact with a pin 57 fast with the flat spring 26 and flex the said spring to such extent that the cam shaped end 29 of the spring projection 28 will pass by the arm 25 and thereby permit the escapement 130

through the action of the ratchet 24 and spring 19 to vibrate the hammer 23 and sound the alarm.

If, however, the owner or authorized operator of the vehicle wishes to move it, he will first turn the dial, and consequently the disk 39, until the number or character previously chosen registers with the indicator 41 on the foot board 11 at which time the blank 44 will have arrived beneath the pin 34 and an attempt at that time to release the lever 50 will merely cause the pin 34 to impinge against the disk 39 and lock it in that position but will not cause the alarm to be sounded.

It will be understood that in practice the exposed parts of the device will be so made as not to be easily removed or disconnected and to this end it is preferred to enclose the gong and its actuating mechanism in a stout box or cover 60 which is normally locked by one means or another in the position shown in Figure 1 of the drawings, but may be unlocked and swung on a hinge 61 when it becomes necessary to wind the alarm or to make adjustments or repairs to the mechanism of the alarm.

Having described the invention I claim:

1. An alarm for vehicles comprising a mechanically operated bell; a brake lever; means including a spring pressed lever and a pin pivotally arranged thereon to release said bell at certain times; a detent for normally holding said bell inoperative, said detent member being arranged to be actuated by said pin when said bell is to be rung; a movable member interposed between said first member and said pin and arranged to separate or permit contact between said first member and said pin to prevent or permit the operation of said bell; and means interposed between said lever and said first means whereby a movement of said lever will cause the operation of said bell when said movable member is in position to permit contact of said pin and said detent.

2. An alarm for vehicles comprising a mechanically operated bell; an emergency brake lever; a normally spring controlled rocking lever; a pin carried by said lever; a bell hammer; means to normally lock said hammer against operation; a disk having a blank spot and a plurality of perforations each side thereof arranged to be alternately positioned beneath said pin; a pin interposed between said first pin and said hammer locking means, and arranged to be operated by said first pin when one of said perforations is positioned beneath said first pin to unlock said hammer upon a movement of said brake lever; and means including a slotted link interposed between said brake lever and said rocking lever whereby said brake lever may be operated regardless of

the position of said rocking lever, and whereby said rocking lever may be actuated at times by said brake lever.

3. An alarm for vehicles comprising a brake lever; a bell; a vibrating hammer for said bell; means to prevent the vibration of said hammer, said means including a spring detent; a spring pressed lever; a pin carried by said lever; and cooperating with said detent; a disk having a plurality of perforations circularly arranged adjacent the perimeter thereof and a solid portion separating certain of said perforations said disk being pivotally arranged to revolve in its own plane; means to revolve said disk; said perforations and said solid portion of said disk being arranged to be alternately interposed between said pin and said detent; and a loose connection between said brake lever and said spring pressed lever whereby said brake lever may be moved in brake unsetting direction relatively to said spring pressed lever when the latter is restrained by said disk, and whereby said spring pressed lever is movable at times with said brake lever to effect the operation of the bell mechanism when said lever is moved in brake-unsetting direction and said spring-pressed lever is not restrained by said disk.

4. The combination with the brake lever of a vehicle, of a bell mechanism; a bell-controlling member that is held against movement in a direction to effect the operation of said bell mechanism by said brake lever when the latter is in brake-setting position; a spring independent of said bell mechanism for securing said member with said brake lever to effect the operation of said bell mechanism when the brake lever is shifted toward brake-unsetting position, and means adjustable so as to lock said bell-controlling member against movement with said brake lever when the latter is moved toward brake-unsetting position and also adjustable so as to permit movement of said bell-controlling member by said spring with said brake lever to effect the operation of the bell mechanism when said brake lever is moved toward brake-unsetting position.

5. The combination with the brake lever of a vehicle, of a bell mechanism; a bell-controlling member that is held against movement in a direction to effect the operation of said bell mechanism by said brake lever when the latter is in brake-setting position and is yieldingly urged in said direction independently of said bell mechanism and lever when said brake lever is shifted toward brake-unsetting position; means adjustable so as to lock said bell-controlling member against movement with said brake-lever in said direction when the latter is moved toward brake-unsetting position and also adjustable so as to permit movement of said bell-con-

trolling member with said brake lever to effect the operation of the bell mechanism when the brake lever is moved toward brake-unsetting position, said means comprising a 5 rotatably adjustable abutment co-operating with said bell-controlling member; a shaft carrying said abutment; a dial on said shaft

accessible to the driver of the vehicle and carrying a scale, and a stationary index co-operating with the scale on the dial. 10

Signed by me at Boston, Massachusetts, this 1st day of February, 1926.

ALBERT V. LOCKE.
